CLAIM

The ornamental design for a plastic container, as shown and described.

DESCRIPTION

FIG. 1 is a top, front and right side perspective view of the plastic container of the present invention showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.

The dash-dash-dash-broken line showing of the container bottom, of the closure, and of the numerous small circular shapes on the sidewall are included for the purpose of showing environmental structure that forms no part of the claimed design.

The dot-dash-dot-dash broken lines shown in the drawings define the boundaries of the claimed design.
